CURTAIN HOLDER

Filed, March 8, 1928

Inventor:
Henry Kasbarian,
by night from Quincy May
Atlys.

UNITED STATES PATENT OFFICE

HENRY KASBARIAN, OF BOSTON, MASSACHUSETTS

CURTAIN HOLDER

Application filed March 8, 1928. Serial No. 259,971.

This invention relates to means for supporting drapery curtains on a window casing, said means including brackets attachable to a window frame, and a curtain-engaging rod or rods supported by the brackets.

The object of the invention is to provide a two-part bracket of simple construction, including an inner member or plate attachable to a window casing, and a curtain-rod supporting arm adapted to be detachably secured to the plate and firmly supported thereby, and to securely support a curtain rod.

The invention is embodied in the improved construction of the plate and arm hereinafter described and claimed.

Of the accompanying drawings forming a part of this specification,—

Figure 1 is a fragmentary perspective view, showing one of the arm members of my improved bracket, and portions of two curtain-rods supported thereby.

Figure 2 is a perspective view of the plate member of the bracket, attachable to a window casing, and adapted to releasably support the arm member shown by Figure 1.

Figure 3 is a perspective view of a plate member of different form.

Figure 4 is a top plan view, showing two of the brackets embodying the invention, supported by a window casing, said brackets constituting elements of a non-adjustable curtain holder.

Figure 5 is a view similar to Figure 4, showing these brackets constituting elements of a holder which is adjustable in length.

Figure 6 is a section on line 6—6 of Figure 9.

Figure 7 is a section on line 7—7 of Figure 6.

Figure 8 is a section on line 8—8 of Figure 7.

Figure 9 is a section on line 9—9 of Figure 7.

45 The same reference characters indicate the same parts in all of the figures.

My improved bracket is composed of two separable members, one of which is a plate 12, adapted for attachments by screws, or otherwise, to a window casing 13. The plate

is preferably a single piece of sheet metal, and is provided with a pair of spaced apart vertical sockets, formed by vertical ears 14 bent from opposite edges of the plate, and horizontal ears 15, bent from the plate, and closing the lower ends of the sockets. The vertical inner edges and upper ends of the sockets are open. The plate is provided with an extension between and projecting below the sockets.

The other member of the bracket is a hollow arm 16, laterally projecting vertical ears 17 at its inner end, removably insertible in the plate sockets, said ears bearing on the closed ends of the sockets. A downwardly projecting horizontal abutment ear 18 (Figures 7 and 9) is formed on the inner end of the arm, and arranged to bear on the portion of the extension of the plate 12 below the sockets, the three ears cooperating with the plate and its sockets in preventing lateral swaying and downward sagging of the arm.

The arm 16 is a short length of seamless tubing, which is rectangular in cross section, so that the plate has flat sides. This form enables the ears 17 to be conveniently bent laterally from the inner ends of the flat inner and outer sides of the tubular arm, and the ear 18 to be formed by downwardly bending the inner end of the flat under side, the inner end of the tubular arm having slits 26 (Figure 6) cut therein to define the ends of the ears and permit the bending thereof from the main portion of the arm. The outer end portion of the tubular arm may be utilized as a socket, to receive a portion of an ornamental terminal shown by Figure 1.

The outer end portion of the arm 16 is apertured, to receive a curtain rod extending between two adjacent brackets, and is provided with a set screw inserted in a tapped orifice in the upper side of the arm, and adapted to engage a rod inserted in the apertured end.

The non-adjustable holder shown by Figure 4, is made by assembling with two of the described brackets, a single rod 20, secured to the arms by the set screws, and an additional rod 21, the ends of which are inserted

in apertures formed only in the inner sides of the two arms 16, as indicated by Figure 6, no set screws being required to secure the arm 21.

5 The adjustable holder shown by Figure 5, is made by assembling with three of the brackets, the sectional rod next described, the brackets being alike, with the exception that the intermediate bracket includes a plate 12^a (Figures 3 and 5) having an ear 12^b adapted to bear on and be attached to a downwardly facing surface on a window casing. The sectional rod is composed of a tubular intermediate section 23, secured by a set screw 19 to the arm 16 of the intermediate bracket, and two end sections 24, slideable in the intermediate section and secured by set screws to the arms 16 of the end brackets.

20 The sockets on the bracket plate, and the ears on the bracket arm are of such form that the sockets may be integral parts of an inexpensive sheet metal plate 12 or 12^a, and the ears may be integral parts of a tubular sheet metal arm which is square in cross section, 25 the arm being, therefore, strong and durable and having an attractive form.

I claim:

1. A curtain-rod bracket comprising a flat-sided plate adapted for attachment to a window casing and provided with spaced apart sockets which are vertically arranged when the plate is attached, and have closed lower ends, open inner edges, and open upper ends, the plate having an extension projecting downwardly between and below the sockets; and a one-piece arm having means for receiving a curtain rod and composed of a length of tubing which is rectangular in cross section and has flat sides, two opposite sides of the arm being extended and bent to form integral vertical ears adapted to enter said sockets and abut the closed ends thereof, the lower side of the arm being extended and bent to form an integral transverse ear adapted to abut the plate extension.

2. A curtain-rod bracket comprising a flat-sided plate adapted for attachment to a window casing and provided with spaced apart sockets which are vertically arranged when the plate is attached, and have closed lower ends, open inner edges, and open upper ends, the plate having an extension projecting downwardly between and below the sockets; and a one-piece arm composed of a length of tubing which is rectangular in cross section and has flat sides, two opposite sides of the arm being extended and bent to form integral vertical ears adapted to enter said sockets and abut the closed ends thereof, the lower side of the arm being extended and bent to form an integral transverse ear adapted to abut the plate extension, the arm being laterally apertured to receive a curtain-rod and provided in its flat upper side with a

tapped orifice containing a rod-engaging set screw.

In testimony whereof I have affixed my signature.

HENRY KASBARIAN.
